UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPLING.

1,099,853.

Specification of Letters Patent.

Patented June 9, 1914.

Application filed April 29, 1910. Serial No. 558,455.

To all whom it may concern:

Be it known that I, HARRY T. KRAKAU, a citizen of the United States, and a resident of Cleveland, Cuyahoga county, State of Ohio, have invented a new and useful Improvement in Car-Couplings, of which the following is a full, clear, and exact description, reference being had to the accompanying drawings, forming part of this specification, in which—

Figure 1 is a plan view partly in section of a portion of a railway car under-framing, showing my invention applied thereto; Fig. 2 is a longitudinal section of the same; Fig. 3 is a detail cross sectional view; Fig. 4 is a perspective view showing one of the thimble plates and thimbles; and Fig. 5 is a view partly in side elevation and partly in vertical section showing a modification.

My invention has relation to coupling mechanism for railway cars, and is designed to provide means for permitting greater vertical movement of the couplers without distortion of their parts when one car makes a vertical angle with another.

I have determined that when two couplers of the ordinary vertical plane type having the regular Master Car Builders' lines are coupled together, when one car makes a vertical angle with another, as in ascending a grade or when the cars pass over a hump, the coupler knuckles bear against each other with tremendous pressure and are either distorted or will distort or break the lugs of the couplers, if the vertical angle exceeds a slight degree. This is due in part to the fact that with this

type of coupler as ordinarily used, there is very little clearance between the buffing faces of the knuckles and the buffing faces of the opposing couplers and also to the rigidity of the attachment of the coupler to the draft rigging and thence to the car.

My invention provides means of simple and effective character whereby this rigidity of attachment is overcome and provision is made for a sufficient vertical movement of the coupler and draft rigging to permit of a considerable vertical angling of the coupled cars without danger of injury to the parts.

Referring to the accompanying drawings, in which I have illustrated a preferred embodiment of my invention and

which will now be described, premising, however, that my invention is susceptible of various modifications in the form and arrangement of the various parts, the numeral 2 designates a coupler having buffing wings or flanges 2^a on the coupler head, and attached by means of bolts 3 to a draft gear casing or housing 4. Within this housing can be placed any suitable shock-absorbing mechanism, such as springs or friction draft gear, adapted to be inclosed by a forwardly extending yoke 5, to act in the usual manner of draft springs and draft gear. The rear end portions of the yoke 5 terminate in thickened portions 5^a which have holes therein for the insertion of a vertical pivot pin 6, about which the coupler and draft gear can swing laterally. As thus far described, the device does not differ essentially from radial draft gears heretofore made. The yoke 5, however, instead of being pivoted by the pin 6 directly to a bolster casting integral with or attached to the car bolster, as is usual, is pivoted to a member or casting 7, which member or casting is, in turn, pivoted at its rear end portion by means of a horizontally extending pin 8 between lugs 9 of a bolster casting 10. By means of this horizontal pivot 8, the coupler and the draft gear to which the coupler is attached can, therefore, swing not only laterally about the pivot 6, but also in a vertical direction, thus compensating for the vertical angling of the cars in passing over a hump of the track or in passing over a straight track to a suddenly ascending or descending grade.

Beneath the coupler shank 2^b is a segmental casting 11, in the shape of a portion of an arc of a circle, whose center coincides with the center of the vertical pin 6. Instead of the shank of the coupler resting directly upon the casting 11 and sliding thereon in its horizontal or lateral movements, I provide upper and lower thimble plate 12, having bosses or thimbles 13. The bosses 13 of the lower thimble plate project upwardly through the bottom portion of the hollow coupler shank and into the interior thereof, while the thimbles of the upper plate project downwardly through the upper wall of the shank. The lower thimble plate is arranged to bear upon the casting or support 11, while the upper

thimble plate is arranged to bear against the under side of the overhanging sill 14. Before the thimble plates are placed in position, centering springs 15 are inserted 5 through a suitable aperture in the coupler shank and are pushed forward so as to come into register with the top and bottom thimble-receiving holes of the shank. The thimbles are then inserted in the holes provided 10 for them and are secured from removal by means of bolts and nuts 16, after which the coupler is ready for its attachment to the draft gear and thence to the car. The ends of the springs 15 bear against washers 17. 15 The thimbles are shown as being of cruciform shape, see Fig. 4, for a portion of their length, and the washers are provided with openings of corresponding form, the washers being free to slide on the thimbles only a 20 portion of the length thereof, by reason of this form. The action of these centering springs will be apparent. They allow the coupler to move vertically either up or down from the normal center line of the coupler, while upon the removal of any force tending to throw the coupler out of such central line, they act to return the coupler and draft rigging to the central position. 25 30 In the modification shown in Fig. 5, the construction is the same as that first described, except that the bottom wall of the coupler shank 2^b is provided with enlarged openings 2^c sufficient to receive not only the 35 bosses of the lower thimble plate, but also the centering springs, 15^a, which in this case are made longer and rest at their lower ends directly upon the thimble plate. The upper ends of the springs rest against the 40 washers 18, which are similar to the washers 17 before described. In this construction, the coupler and attached draft rigging are spring resisted only against downward movement. If raised above this normal 45 central position, gravity will insure its return to the center line as soon as the distorting force ceases to act.

The advantages of my invention result from the provision of means for permitting 50 sufficient vertical movement of the coupler and draft rigging to compensate for vertical angling of the cars and from the provision of means whereby the coupler in the absence of any force acting to move the coupler and draft rigging out of its normal 55 position will be held in such position. It will be obvious that various arrangements of centering springs may be provided for this pur-

pose, that the invention is applicable to other forms of couplers and draft gear than 60 the form which I have shown and described and that various other changes may be made in the details of construction and arrangement of the parts, without departing from the spirit and scope of my invention as defined in the appended claims. 65

I claim:

1. In car coupling mechanism, a draft member comprised of a coupler and a draft rigging, the draft member having a universal connection with the car, a vertical guide member passing through the draft member, upon which the coupler is guided in its vertical movements, and a spring seated upon the guide member within the draft member and adapted to yieldingly center the draft member in normal horizontal position. 70

2. In car coupling mechanism, the combination with a coupler mounted for vertical 80 movement, of a segmental casting below the coupler shank, thimble plates mounted on said segmental casting and having vertically extending bosses or thimbles which pass through said shank, and springs surrounding said thimbles within the shank and acting upon the coupler shank to center the coupler vertically; substantially as described. 85

3. In car coupling mechanism, the combination with a coupler shank mounted for vertical movement, of upper and lower thimble plates, having thimbles passing through the coupler shank, washers seated on said thimbles, springs interposed between the washers within the coupler shank, and supporting means for the thimble plates; substantially as described. 90 95

4. In car-coupling mechanism, a coupler, a draft rigging mounted and connected for both vertical and lateral movements, a supporting member extending underneath the shank of the coupler, a bearing overhanging the shank of the coupler, and centering devices carried by the shank of the coupler and arranged to engage said support and bearing, said devices comprising thimble members extending into the shank of the coupler, and a spring seated upon said members within the coupler shank, substantially as described. 100 105

In testimony whereof, I have hereunto set my hand:

HARRY T. KRAKAU.
